DESIGN FOR A SHOE LACING

Burton L. Wales, Abington, Mass., assignor to The Stetson Shoe Company, Incorporated, Weymouth, Mass., a corporation of Massachusetts

Application September 23, 1938, Serial No. 80,059

Term of patent 3½ years

To all whom it may concern:

Be it known that I, Burton L. Wales, a citizen of the United States of America and a resident of Abington, in the county of Plymouth, Commonwealth of Massachusetts, have invented a new, original, and ornamental Design for Shoe Lacings, of which the following is a specification, reference being had to the accompanying drawing, forming part thereof.

In the drawing:

The figure is a perspective view of the shoe lacing showing my new design.

I claim:

The ornamental design for a shoe lacing, substantially as shown.

BURTON L. WALES.
